UNITED STATES PATENT OFFICE.

WILLIAM O. RENKIN, OF ORADELL, NEW JERSEY, ASSIGNOR TO QUIGLEY FURNACE SPECIALTIES CO., INC., A CORPORATION OF NEW YORK.

APPARATUS FOR HANDLING PULVERIZED FUEL.

1,308,367.

Specification of Letters Patent.

Patented July 4, 1919.

Application filed November 30, 1917. Serial No. 204,788.

To all whom it may concern:

Be it known that I, WILLIAM O. RENKIN, a citizen of the United States of America, residing at Oradell, county of Bergen, State of New Jersey, have invented certain new and useful Improvements in Apparatus for Handling Pulverized Fuel, of which the following is a specification.

My invention relates to apparatus for feeding pulverized materials in regulated quantities and is more particularly designed for use as a "controller" for handling pulverized coal, regulating the rate at which the same is fed to a combustion apparatus in which it is to be burned, and delivering said regulated quantities at a uniform rate. The best form of apparatus at present known to me embodying my invention is illustrated in the accompanying four sheets of drawings in which—

Figure 1 is a side elevation of the apparatus.

Fig. 2 is a cross section on line 2—3 of Fig. 1, showing the parts in position assumed when the feed regulating device is closed, and

Fig. 3 is a similar view showing it open.

Fig. 4 is a detail of the feed screw.

Fig. 5 is a detail side elevation and

Fig. 6 is a section on line 6—6 of Fig. 5, showing a modified form of distributing device, parts being broken away.

Fig. 7 and Fig. 8 are similar views of a second modification, and

Fig. 9 is a detail side view of the cam used therein.

Fig. 10 is a side view and

Fig. 11 a cross section on line 11—11 of Fig. 10, showing in detail the upper cut-off blade.

Figs. 12 and 13 show a modified form of feed regulating device.

Throughout the drawings like reference characters indicate like parts.

1, is the lower portion of a hopper or other receptacle containing a mass of the pulverized material to be fed, which receptacle has an opening in one wall at a point a substantial distance above the bottom of the receptacle and substantially centrally of the wall communicating with conduit 2, extending therefrom. 3, is a screw conveyer extending through the hopper interior and through conduit 2, journaled at either end at points

4, 4. Usually this screw is driven by bevel

gear 5, meshing with beveled pinion 6, on shaft 7, carrying belt pulley 8. Rotation of screw 3, in a counter-clockwise direction tends to force material from hopper 1, through conduit 2, into screening or distributing chamber 9. As shown, the cross section of the receptacle at the bottom of the hopper in which the conveyer screw is located, is considerably larger than the cross section of the conveyer screw 3, which lies in it.

Chamber 9, has an inlet 10 in its upper portion, through which screw 3, projects pulverized material into its interior, and an outlet opening 12, at the bottom through which the said material drops to the ejector 13, operated by compressed air in the usual way. Between these inlet and outlet openings is interposed a reticulated member or screen 11, of any suitable form, on which the material discharged from conduit 2, may fall. This material usually drops from the screw 3, in aggregated masses and it is important in many cases to break these up into a steady stream of individual particles to be fed to the ejector 13. To effect this a reciprocating or jiggling motion of some sort should be given to screen 11. This may be done in a number of ways, and constitutes one feature of my invention.

In Fig. 1 the screen 11, is in the form of a truncated cone with its smaller end sliding freely on the projecting end of the conduit 2, and its larger end sliding on the shaft of screw 3. Pin 47, fixed in the end wall of chamber 9, engages the spider 48, supporting the larger end of screen 11, and prevents its rotation with the screw. 49, is a hub on screw 3, with cam groove 50, in which runs pin 51, carried by spider 48. As a result the spider and screen cannot rotate and the revolutions of screw 3, will, through cam groove 50 and pin 51, cause rapid longitudinal reciprocation of the screen and so distribute the material deposited on the screen evenly through its meshes and cause said material to fall into ejector 13, in a uniform continuous shower of small particles rather than in aggregated masses.

The control or regulation of the flow of material to screen 11, or other distributing device, is effected by the adjustment of a plurality of cut-off blades encompassing feed screw 3, which has its thread cut away or notched at 14, (see Fig. 4) to receive such

blades 15 and 16, which are adjustable radially of the screw. The number of blades and the form of their adjusting means may be varied, but I have shown a pair of blades 5 pivoted on shafts 17, and 18, journaled in the hopper wall and operated by bell cranks 19, and 20. The latter have bifurcated ends loosely engaging pins on nuts 21, 22, mounted on regulating screw 23, journaled in 10 hanger 24. When this screw is rotated by hand or through any suitable means such as universal joint connection 25, the blades 15 and 16, are simultaneously swung toward or from screw 3. These blades have semicircular notches 26, formed in their edges next to screw 3, and of the same radius as that of the shaft of screw 3, so that when they fit into notch 14, the blades closely encompass the screw shaft and completely close the outlet from the hopper. When this is done, as shown in Fig. 2, continued rotation of screw 3, merely causes the pulverized material in hopper 1, to mushroom out along the end wall of the hopper and travel back along 20 the bottom and side walls and top, thus setting up a local circulation of the material in the hopper which absorbs practically no more power than does the straight feeding operation which takes place when the blades 25 are swung apart as shown in Fig. 3. To facilitate this operation the working faces of blades 15 and 16, are preferably given a cone shape as shown at 27, in Fig. 11. By rotating screw 23, the blades 15 and 16, may 30 be set at any intermediate point and an exact adjustment of the feeding of the material to screen 11, thus secured to any desired degree from full delivery to zero.

In the modified distributing apparatus of Figs. 5 and 6, the larger end of screen 11, is hung from hanger 30, by pivot pin 31, so as to swing transversely of the screw 3, while its smaller end is supported by universal joint 32, on the end of conduit 2. The spider 45 35, in the larger end of screen 11, has a yoke 33, in which rotates cam 34, on the shaft of screw 3. Rotation of the screw then swings the screen from side to side through coöperation of this cam and yoke.

In the form shown in Figs. 7, 8 and 9, screen 11, is hung by pivots 42, 42, on two links 40, 40, pivoted at 41, 41, so as to swing in the plane of the axis of screw 3, forming a "parallel ruler" construction. A double cam 43, mounted on screw 3, having long inclined faces 45, 45, and short, drop faces 46, 46, coöperates with pins 44, 44, on the smaller end of screen 11, to give the same frequent and sudden reciprocations lengthwise of 60 said screw 3.

A modified form of feed controlling apparatus is shown in Figs. 12 and 13, where the cut-off blades 55, 56, are mounted on shafts 57 and 58, journaled in the hopper 1, 65 above the feed screw 3. These are caused to

open or close simultaneously like a pair of shears by intermeshing gears 59, 60. One of the shafts, as 58, is positively oscillated by bell crank arm 52, connected by link 53, to the fork 54, on the end of screw 63, mounted in nut 65, journaled in housing 64, on the hopper. 62, is a hand wheel by which nut 65, may be rotated. 61, 61, are jam-nuts near either end of the screw 63, and serving as adjustable stops to limit its motion through nut 65.

From many points of view the construction illustrated in Figs. 12 and 13, is the preferred arrangement of cut-off blades, as they open and close on a vertical line, and also give a broader and more rapid opening at the bottom. This allows the material to feed evenly along the bottom of the conduit, no matter what the amount of opening. In the operation of screw conveyers the greatest rate of flow of material is always along the under side of the screw. If the bottom of the conduit is left free from obstruction there will be a continuous flow along it no matter how narrow or wide the opening between the cut-off blades 55, 56. When, however, the line of division or meeting between the cut-off blades is horizontal as in Figs. 2 and 3, the main current of material traveling along under the conveyer screw will tend to bank up against the lower blade 16, (when the blades are partly opened) and then drop over in successive masses. This interferes with the uniform feeding of the material at any time except when the blades are wide open.

The advantages of my invention comprise mainly simplicity of construction, accuracy of feed control and maintenance of a uniform rate of supply at all adjustments of the feeding apparatus.

If desired, the shaft 25, could be operated automatically in unison with the controller of the compressed air supplied to ejector 13.

In all of the forms shown herein the relatively large cross section of the receptacle 1, in which the screw is mounted, as compared with the cross section of the screw itself, permits the material being fed to free itself easily from the screw by moving out readily in all directions when its forward motion is blocked by partial or entire closure of the cut-off blades.

Various changes could be made in the details of construction here illustrated without departing from the principle and substance of the invention and general plan of operation here described.

Having described my invention, I claim:

1. In an apparatus for feeding pulverized fuel the combination, of a receptacle having a circular opening in one of its substantially vertical walls, an exterior cylindrical conduit registering with said opening, a conveyer comprising a shaft with a helix sur-

rounding the same extending from the interior of said receptacle out through said opening and along said conduit, and having its helix interrupted for a short distance just 5 inside the receptacle wall, means for continuously rotating said conveyer at a uniform speed, a pair of cut-off blades pivoted to the inner face of the perforated wall above the opening therein and adapted to fit into 10 the space in the interrupted helix and having their inner edges cut away to closely embrace the conveyer shaft at said point and meet along a substantially vertical line above and below it, thereby preventing the 15 passage of any material out through the opening in the receptacle wall, and means for simultaneously moving said blades more or less toward or from one another whereby a passage of variable width but of a height 20 equal to the vertical diameter of the conduit is opened between receptacle and conduit, through which varying passage the constantly rotating conveyer will force correspondingly variable quantities of material. 25 2. A combination such as set forth in claim 1 in which the cut-off blades are formed with surfaces sloping from the conveyer shaft toward the receptacle wall when they meet around said shaft. 30 3. In an apparatus for feeding pulverized fuel the combination, of a receptacle having a circular opening in one of its substantially vertical walls, an exterior cylindrical conduit registering with said opening, a conveyer comprising a shaft with a helix surrounding the same extending from the interior of said receptacle out through said opening and along said conduit, and having its helix interrupted for a short distance 35 just inside the receptacle wall, means for

continuously rotating said conveyer at a uniform speed, a pair of cut-off blades pivoted to the inner face of the perforated wall and adapted to fit into the space in the interrupted helix and having their inner edges cut 45 away to closely embrace the conveyer shaft at said point and meet along a diameter thereof, thereby preventing the passage of any material out through the opening in the receptacle wall, and means for simultaneously moving said blades more or less toward or from one another whereby a passage of variable area is opened between receptacle and conduit, through which varying passage the constantly rotating conveyer 50 will force correspondingly variable quantities of material.

4. A combination such as set forth in claim 3 in which the cut-off blades are formed with surfaces sloping from the conveyer 55 shaft toward the receptacle wall when they meet around said shaft.

5. In an apparatus for feeding pulverized fuel a receptacle having a circular opening in one of its vertical walls, and a conveyer screw located in said receptacle and projecting out through said opening, said conveyer screw being of a diameter considerably less than the cross sectional dimensions of the receptacle interior, and having its helix interrupted at a point adjacent the receptacle wall, combined with a pair of cut-off plates adapted to move toward and from the screw along the receptacle wall and by entering the space left by the interrupted helix close 70 about the screw shaft, and means for simultaneously moving said plates toward or from the screw and means for rotating the screw 75

WILLIAM O. RENKIN.
